US00D543978S

(12) **United States Design Patent** (10) **Patent No.:** **US D543,978 S**
Kawase (45) **Date of Patent:** **** Jun. 5, 2007**

(54) **COMPUTER**

(75) Inventor: **Atsushi Kawase**, Tokyo (JP)

(73) Assignee: **Sony Corporation**, Tokyo (JP)

(**) Term: **14 Years**

(21) Appl. No.: **29/240,865**

(22) Filed: **Oct. 20, 2005**

(30) **Foreign Application Priority Data**

Aug. 8, 2005 (JP) D2005-022956

(51) **LOC (8) Cl.** **14-02**

(52) **U.S. Cl.** **D14/337**

(58) **Field of Classification Search** D14/336,
D14/337, 371, 125-129; 345/87, 104, 156,
345/168, 173; 348/180, 184, 325, 739; 349/1,
349/2, 11, 62

See application file for complete search history.
